MACHINE FOR BUNCHING MATCH STICKS.

No. 281,408.

Patented July 17, 1883.

UNITED STATES PATENT OFFICE.

WILLIAM H. H. SISUM, OF BROOKLYN, NEW YORK.

MACHINE FOR BUNCHING MATCH-STICKS.

SPECIFICATION forming part of Letters Patent No. 281,408, dated July 17, 1883.

Application filed January 5, 1883. (No model.)

To all whom it may concern:

Be it known that I, WILLIAM H. H. SISUM, of Brooklyn, in Kings county, and State of New York, have invented a certain new and 5 useful Improvement in Machines for Bunching Match-Sticks, of which the following is a specification.

This improvement consists in novel means whereby the match-sticks are kept from clogging the hopper from which they are fed.

It also consists in a novel combination of rollers whereby the match-sticks are taken from the hopper and delivered between two webs.

15 It also consists in a novel combination of parts for supporting standards which sustain the shaft of the roller on which the webs and match-sticks are wound.

It also consists in connecting a driving pinion or wheel by friction-clamps to the shaft of 20 the roller on which the webs and match-sticks are wound.

In the accompanying drawings, Figure 1 is 25 a sectional plan or top view of a machine embodying my improvement. Fig. 2 is a longitudinal section of the same taken on the plane of the dotted line $x x$ in Fig. 1. Fig. 3 is a transverse section of the same taken on the plane of the dotted line $y y$ in Fig. 2. Fig. 4 30 is a transverse section of the same taken on the plane of the dotted line $z z$ in Fig. 1; and Fig. 5 is a side view of a portion of the machine.

Similar letters of reference designate 35 corresponding parts in all the figures.

A designates a hopper in which the match-sticks are placed. A roller, A', having a notched or fluted periphery, has its journals supported in slotted bearings s in the sides of 40 the hopper. One of the journals is provided with a crank whereby it may be turned. The roller preferably will be made of metal. If the match-sticks get crossed, they will raise this roller in its bearings. When this is observed the attendant can by a turn of the roller straighten out the match-sticks again.

The front and back of the hopper are severally composed of two sections, a' a' b' b', the lower of which are pivoted to the upper. The 50 lower pivoted section of the back is provided with studs, which extend through slots in the

sides of the hopper and have fitted to them rods A². These rods are arranged close to the sides of the hopper, and are connected to a bar, A³, which is connected to the lower pivoted 55 section of the front of the hopper and extends through slots in the sides of the hopper. This bar A³ has fitted to it a rod, A⁴, which is connected by a strap, in the usual or any other way, to an eccentric, B, on a shaft, B'. The 60 shaft B' is journaled in bearings in the frame of the machine, and is provided with a pinion, B², which derives motion from a gear-wheel, B³, mounted loosely on a stud extending from the side of the hopper. The gear-wheel B³ 65 derives motion from a gear-wheel, B⁴, which is affixed to a gear-wheel, B⁵, and with it is mounted loosely on a stud extending from the machine. The gear-wheel B⁵ derives motion from a gear-wheel, B⁶, which is arranged upon 70 the driving-shaft C of the machine.

On the driving-shaft C a large gear-wheel, C', is loosely mounted, and derives motion from a small gear-wheel, D, on a counter-shaft, D'. This counter-shaft derives motion 75 from a belt applied to a pulley, D². The driving-shaft C is provided with a clutch-piece, C², which is keyed to the shaft, so as to turn therewith, but is capable of movement lengthwise of the shaft in order that it may be engaged with or disengaged from the gear-wheel C'. A lever, C³, serves as a convenient means for operating this clutch-piece. When the clutch-piece is engaged with the gear-wheel C', the machine is put in motion, and when 85 the clutch-piece is disengaged from the said gear-wheel, the machine is stopped. While the machine is running the eccentric B swings the pivoted sections of the hopper to and fro and facilitates the proper delivery of the match-sticks.

E designates a roller arranged upon the driving-shaft C at the bottom of the hopper and serving to deliver the match-sticks therefrom.

95 F designates a roller arranged close to and just beyond the face of the roller E and receiving the match-sticks from it. The roller F is journaled in bearings in the frame of the machine. The roller E, as here shown, has notches c, extending across its periphery in directions parallel with its axis; but these 100

notches are interrupted by circumferential grooves d , in which fit fingers G . The match-sticks pass from the hopper into these notches e , and are carried away to the roller F . When resting in the notches, they extend across the fingers G . By raising the fingers the match-sticks can be prevented from entering the notches. The roller F has a cylindrical body, e , and flanges f , which are provided with notches g , extending parallel with the axis, and adapted to receive the match-sticks.

It will be observed that the match-sticks pass over the roller E to a point about horizontally opposite the axis of the roller, and there are transferred to the roller F . The roller F rotates in the opposite direction to the roller E ; hence the match-sticks, when transferred to the roller F , pass first under the same and thence upward.

H designates guards which extend around and close to the portions of the notched flanges of the roller F , which the match-sticks traverse, and thereby aid in holding the match-sticks in the notches of this roller. At the upper ends these guards H are reverted or bent to conform to the periphery of the roller E , and have pointed ends, which extend beyond the bottoms of the notches in the roller E , which are adjacent to the roller F . They are thereby made to constitute strippers for removing the match-sticks from the roller E to the roller F . The match-sticks pass from one to the other of these rollers without any abrupt change of direction.

J The journal of the roller F , which is adjacent to the gear-wheel B^6 , is provided with a gear-wheel, F' , which engages with and derives motion from the gear-wheel B^6 . As here shown, the gear-wheels B^6 and F' are of about the same size.

The fingers G are rigidly affixed to a rock-shaft, G' , which is journaled in bearings in the frame of the machine. On one end this shaft is provided with an arm or crank, G^2 , whereby it may be shifted. By raising the outer end of this arm or crank the fingers may be raised so as to prevent match-sticks from entering the notches of the roller E . A spring, G^3 , fastened to the frame of the machine, has a tendency to move outward, and when the said arm or crank is raised, will move under it and sustain it in its elevated position. When it is desirable to lower the fingers, this spring is pressed inward and the arm or crank allowed to descend. In this way the feeding of the match-sticks may be stopped at any time without stopping the machine as a whole. The fingers pass through notches in the lower section of the front of the hopper; hence no match-sticks can pass between this section and the fingers.

I designates a small roller arranged in a cavity in a guard, a^2 , which is located below the lower pivoted section of the back of the hopper. This guard is stationary, and its upper edge is provided with a number of teeth

which intervene between corresponding teeth on the lower edge of the pivoted section of the back of the hopper; hence no match-sticks can pass between these parts. The small roller I has in its periphery a number of small notches extending parallel with its axis, and it bears against or extends very close to the roller E . It is journaled in bearings I' , (see particularly Fig. 5,) which are susceptible of sliding along rods I^2 . Springs I^3 impinge against the bearings and tend to force the small roller I downward against the roller E , and these springs are attached to rock-shafts I^4 . The rock-shafts I^4 are provided with arms I^5 , in which are fitted screws I^6 , bearing against the frame of the machine. By adjusting these screws the rock-shaft may be shifted so that the tension of the springs will be increased or lessened. If a match-stick is presented to the small roller I , the latter will rise with its bearings, if necessary, and will throw back the match-stick, it being rotated in the same direction as the roller E . The small roller I has affixed to one of its journals a pinion, I^7 , which engages with and derives motion from the gear wheel B^4 . Owing to the relative proportions of the gear-wheels through which the small roller derives motion its periphery moves very much faster than the periphery of the roller E .

J designates a roller on which is wound a strip of webbing, J' . This webbing extends from the roller J through guides h h^2 on back of the hopper, and thence around the body e of the roller F . It passes to this roller F before the match-sticks are transferred to this roller; hence the match-sticks are delivered onto the roller outside of it. From the roller F this webbing passes to a roller, K , which is journaled in bearings in the frame of the machine.

L designates a roller on which is wound a strip of webbing, L' , which passes thence around a guide roller or bar, L^2 , and thence around the roller F , outside the match-sticks. This webbing passes, with the webbing J' , from the roller F to the roller K . The two webs as they leave the roller F carry off the match-sticks between them at regular distances apart, and are wound upon the roller K with the match-sticks between them. The roller K is mounted on a shaft, K^4 , supported in bearings in standards K' . These standards are mounted on bearings j , which are concentric with a shaft, M , supported in the frame of the machine. Hence as the coil or roll of the webs and match-sticks increases in size the roller can move away from the roller F . The roller can be moved so far back that its shaft will rest upon a post or support, K^2 . On the shaft K^4 , which supports this roller K , is a pinion, K^3 , which engages with a large gear-wheel, M' , arranged on a shaft, M , which is journaled in the frame of the machine. On the shaft M is also a gear-wheel, M^2 , which engages with a gear-wheel, N , on a shaft, N' . The gear-wheel N engages with and derives motion

from the gear-wheel F'. The gear-wheels B⁶, F', N, and M² are shown as of the same size. When a roll or coil of the webs J' L and the match-sticks is completed, it and the roller are slipped off the shaft which supports the roller, and all are removed to the place where the igniting material is to be applied to the match-sticks. To permit of the removal of the roller K it is fitted loosely on its shaft and caused to rotate therewith by means of a spline or feather. When this roller is removed it will be replaced by another.

The standards K' are shown as united in one casting, which comprises a cylindric base-piece that fits on cylindric bearings extending inwardly from opposite portions of the frame of the machine. They are therefore not affected by the rotary movement of the shaft M.

The pinion K³ is not rigidly affixed to the shaft K⁴, but is secured thereto by clamps K⁵. One of these clamps bears against a collar, k, on the shaft, and the other is forced and held against the pinion by means of a nut, K⁶, and a jam-nut, K⁷. Both clamps are faced 25 with leather or analogous material. By tightening or loosening the nuts more or less friction may be produced. This connection of the pinion with its shaft allows of the slipping of the roller when the roll of webs and match-sticks materially increases in size.

In another application for Letters Patent, filed May 26, 1883, and of which the serial number is 96,193, I have claimed the combination, with a roller onto which match-sticks are delivered, of two webs or bands between which the match-sticks are carried off, a roller onto which the webs or bands with the match-sticks are wound, and a pinion or wheel mounted on the shaft of the last-named roller and secured by a friction-clamp, so that it may slip on the shaft when necessary. This subject-matter was, but is not now, claimed in this application.

I am aware of Letters Patent No. 37,562, granted February 3, 1863, to A. and E. B. Beecher, for a machine for framing lucifer-match sticks for dipping, and I do not intend to cover by my claims anything shown therein. In said patent there is shown a machine comprising a hopper and rollers or wheels for taking match-splints from the hopper and placing them between two bands or pieces of webbing; but the arrangement and manner of operation of these rollers is essentially different from that shown and hereinbefore described by me.

What I claim as my invention, and desire to secure by Letters Patent, is—

1. The combination, with a hopper having its front or back, or both, provided with a pivoted lower section or sections, and a roller arranged therein for carrying the match-sticks from the hopper, of means for imparting a positive and constant vibrating or swinging motion to said section or sections in a direc-

tion transverse to the length of said roller, substantially as specified.

2. The combination, with a hopper having opposite sides provided with pivoted lower sections, a roller arranged in the hopper for carrying the match-sticks from the hopper, and means for imparting a positive rotary motion to the roller independently of the weight of the contents of the hopper, of means connecting the pivoted sections, so that they will move in unison, and devices for imparting a positive and constant vibrating or swinging movement to said sections, substantially as specified.

3. The combination, with a hopper having opposite sides provided with pivoted sections, of means connecting them, and means acting on one of the pivoted sections to vibrate both, substantially as specified.

4. In a machine for bunching match-sticks, the combination of a hopper in which the match-sticks are placed, and a roller having a notched or fluted periphery and journaled in slotted bearings, so that it can rise bodily when necessary, substantially as specified.

5. In a machine for bunching match-sticks, the combination of a hopper wherein the match-sticks are placed, a large roller for carrying the match-sticks from the hopper, a small metal roller having a fluted or notched periphery arranged at the point where the match-sticks leave the hopper, and means for rotating it at a high rate of speed, and a roller, A', having a fluted or notched periphery journaled in the sides of the hopper, above the said large roller, and adapted to be turned to straighten the match-sticks, substantially as specified.

6. In a machine for bunching match-sticks, the combination of a hopper in which the sticks are placed, a large roller for carrying the match-sticks from the hopper, and a small metal roller having a fluted or notched periphery arranged in movable or yielding bearings at the point where the match-sticks leave the hopper, and adapted to rotate at a high rate of speed, substantially as and for the purpose specified.

7. The combination, with the hopper A, of the two rollers E F, both having notched peripheries, mechanism for rotating said rollers in reverse directions and at uniform speeds, so that their notches will come opposite each other, and the guards and strippers H, extending close to the notched flanges f of the roller F, and thence in a reverse direction beyond the bottoms of notches in the roller E, which are adjacent to the roller F, substantially as specified.

8. The combination, with a hopper, A, of the roller E, having a notched periphery and grooves d, the roller F, having a cylindric body and notched flanges f, which are opposite the grooves d, the webs J' L', mechanism for rotating said rollers in reverse directions and at a uniform speed, so that the notches will

come opposite each other, and the guards and strippers H, extending around the lower part of the flanges f and the upper part of the roller E and resting in the grooves d, substantially as specified.

9. In a machine for bunching match-sticks, the combination of the shaft K⁴, the pinion K³, the shaft M, and wheel M', the standards K', carrying the shaft K⁴, and projecting from 10 a cylindric base-piece which surrounds the shaft M, and bearings j, projecting from the frame of the machine around the shaft M, and entering and supporting the said cylindric base-piece, substantially as specified.

10. In a machine for bunching match-sticks, 15 the combination, with a hopper in which the match-sticks are placed, of a roller having a notched periphery rotating in the hopper, and fingers normally extending into circumferential grooves in the roller, and adapted to be 20 raised to preclude the entrance of match-sticks into the notches of the roller, substantially as specified.

WM. H. H. SISUM.
